(57) **CLAIM**

The ornamental design for a dual headed USB flash drive, as shown and described.

DESCRIPTION

FIG. 1 is a front perspective view of a dual head USB flash drive showing our design.

FIG. 2 is a rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front perspective view thereof, showing the dual head USB flash drive in a first use state; and,

FIG. 10 is another front perspective view thereof, showing the dual head USB flash drive in a second use state.

The broken lines in the drawings show portions of the dual headed USB flash drive that form no part of the claimed design.

1 Claim, 10 Drawing Sheets
